Primary Examiner — Steven J Czyz(57) **CLAIM**

The ornamental design for a jewelry tower, as shown and described.

DESCRIPTION

FIG. 1 is a front, top perspective view of a jewelry tower design showing my new design.

FIG. 2 is a front view of the jewelry tower.

FIG. 3 is a rear view of the jewelry tower.

FIG. 4 is a left view of the jewelry tower.

FIG. 5 is a right view of the jewelry tower.

FIG. 6 is a top view of the jewelry tower; and,
FIG. 7 is a bottom view of the jewelry tower.

The broken lines depict portions of the article that form no part of the claimed design.

Any shading and cross-hatching are not features of the design but are utilized to illustrate the surface contours of the jewelry tower design in the drawings.
